UNITED STATES PATENT OFFICE.

EDGAR JOHN YOUNG, OF BUENOS AYRES, ARGENTINA.

APPARATUS FOR READING STADIA.

No. 922,833.

Specification of Letters Patent. Patented May 25, 1909.

Application filed May 24, 1906. Serial No. 318,595.

To all whom it may concern:

Be it known that I, EDGAR JOHN YOUNG, a citizen of the United States, residing at the city of Buenos Ayres, Argentine Republic, 5 have invented certain new and useful Improvements in the Apparatus for Reading Stadia, of which the following is a specification, reference being had therein to the accompanying drawings.

10 My invention has for its object a new system of measuring distance with a telemeter whereby the errors which are a part of the system now employed will be eliminated. I accomplish this result by the use of a new 15 and improved apparatus for reading stadia.

I will first describe my invention as illustrated in the accompanying drawings, and then point out the invention in the claim.

In the drawings: Figure 1 is a general view 20 of my improved apparatus. Fig. 2 is an illustrative view showing the operation with my improved apparatus.

a represents an ordinary tripod provided with the plumb bob b.

25 c is a spindle which is supported vertically on a horizontal plate, which plate is connected to the tripod by means of the adjusting screws d. Turning on the spindle c is the limb e.

30 f and g are sockets or guides. Passing into the socket f is the rod h and passing into the socket g is the rod i. These rods h and i are, as shown, graduated. These rods h and i are secured in their respective sockets f and g by 35 means of the clamp screws j. Supported upon the limb e are the sight vanes k in line with each other, which line is at right angles to the line through the center of the sockets or guides f and g.

40 l is a frame projecting vertically from the limb e.

m is a wire, one end connected to rod h, the other end connected to rod i, said wire passing over the top of frame l.

45 o is a clamp screw adapted to clamp wire m to frame l.

p is a plain target movable upon rod h and adapted to be secured thereto at the desired position, by means of a clamp screw, not 50 shown.

q is a target provided with a vernier r operated by a tangent screw, not shown. This target q is movable upon rod i and is secured thereto by means of a clamp screw, not 55 shown.

s is a fixed target carried by the upright

frame l. This target is in a vertical line coincident with the plumb bob.

In operating with this new stadia apparatus, instead of having the wires in the transit 60 horizontal, they are vertical. The apparatus is leveled as an ordinary compass would be. The limb e is leveled by means of the adjusting screws d and level t. The deflection of h and i from a horizontal line is corrected by means of wire m, which when these rods are brought into a horizontal condition is clamped by means of the clamp o. The rods h and i are then fixed in their sockets and clamped. The target p is clamped on a 65 division corresponding to about one half of the estimated distance to be measured. The telemeter u is then set up and the vanes 70 k brought into alinement therewith. The limb e is then clamped by clamp screw v. 75

As before stated, the stadia wires w in the telemeter u, to read the distance with this apparatus, are placed vertically instead of horizontally. The telemeter being adjusted, the operation is as follows: Sight the left 80 hand stadia wire on the center of target p. In connection with a prearranged signal, the rod man will slide target q along rod i until nearly in line with the right hand stadia wire. This target is then clamped. The 85 tangent screw is then operated to move the vernier r to bring about an exact coincidence and thus read the intercepted distance between targets p and q. By this arrangement, as may be seen, I employ two targets 90 with vernier, reading the telemetric distance intercepted on the horizontal rod at right angles to the line of collimation. The interval factor of the wires being known: distance between points = intercepted distance 95 on rod $\times$ internal factor + focal correction.

The bearing is determined by observing s. This method of telemetry implies the following corollaries: 1st. By adjustment p and q are practically equidistant and at right angles to the line of vision, also their horizontal plane forms with the stadia wires an angle of 100 90° , hence the intercepted distance on p q is 105 always proportional to the distance between the points of observation + focal correction. 2d. The correction for reducing to 90° the angle of incidence of the vision with the vertical plane of the rod, when observing from different levels, is hereby eliminated. 3d. It also eliminates the error arising from refraction, owing to the greater density of the 110 atmosphere traversed by the lower wire in

the system now in practice. The vertical wires intercept a horizontal distance, therefore in an atmosphere of homogeneous density.

Having now fully described my invention, what I claim and desire to protect by Letters Patent is:

An improved apparatus for reading stadia comprising a central support, opposite rods projecting horizontally from said support, vanes on said support in a line at right angles to the line of the rods at a point central

of said apparatus, a target movable upon each of said rods, a frame, a wire connected to said rods and passing over said frame, and a clamping device to secure said wire to said frame.

In testimony whereof I have affixed my signature in the presence of two witnesses.

EDGAR JOHN YOUNG.
